SLIDE RULE

Addison W. Learned III and Rosalie C. Learned, both of 88 Dorset Road, Holliston, Mass. 01746

Filed Aug. 5, 1970, Ser. No. 24,314

Term of patent 7 years

Int. Cl. D10—99

U.S. Cl. D52—6

FIG. 1 is a top plan view of a slide rule showing our new design;

FIG. 2 is a right end view of FIG. 1, the opposite view being a mirror image thereof;

FIG. 3 is bottom edge view of FIG. 1, the top edge view being a mirror image thereof; and

FIG. 4 is a top plan view of FIG. 1 wherein the slide portion is in an extended position.

We claim:

The ornamental design, for a slide rule, substantially as shown and described.
